(57) CLAIM

The ornamental design for a t-shirt, as shown and described.

DESCRIPTION

FIG. 1 is a front elevation view of a t-shirt showing my new design;

FIG. 2 is a rear elevation view thereof;

FIG. 3 is a front perspective view thereof;

FIG. 4 is a rear perspective view thereof;

FIG. 5 is a left side elevation view thereof;

FIG. 6 is a right side elevation view thereof;

FIG. 7 is an enlarged front view thereof; and,

FIG. 8 is an enlarged rear view thereof.

The broken line showing of environment is for illustrative purposes only and forms no part of the claimed design.
